CLAIM

The ornamental design for an element of an eyewear temple, as shown and described.

DESCRIPTION

FIG. 1 is a perspective view of an element of an eyewear temple showing my new design;

FIG. 2 is a front elevational view thereof, with the rear side being a mirror image of that shown;

FIG. 3 is a left side elevational view thereof;

FIG. 4 is a right side elevational view thereof;

FIG. 5 is a top side elevational view thereof;

FIG. 6 is a bottom side elevational view thereof; and,

FIG. 7 is a perspective view thereof, the broken line showing of the entire eyewear temple is for illustrative purposes only and forms no part of the claimed design.
